(57) **ABSTRACT**

A common-mode choke coil includes a multilayer body, a first coil, and a second coil. The multilayer body is a cuboid in shape that includes plural stacked non-conductor layers. The first and second coils are incorporated in the multilayer body. The first coil includes a first coil conductor, and the second coil includes a second coil conductor. The first coil conductor is positioned with gaps SG1 to SG4 interposed between the first coil conductor and the outer periphery surface of the multilayer body. The second coil conductor is positioned with gaps SG5 to SG8 interposed between the second coil conductor and the outer periphery surface of the multilayer body. Of the four absolute values of the differences between the gaps SG1 to SG4 and the corresponding gaps SG5 to SG8, at least two absolute values are greater than or equal to 0.02 mm.

COMMON-MODE CHOKE COIL

CROSS-REFERENCE TO RELATED APPLICATION

This application claims benefit of priority to Japanese Patent Application No. 2020-017322, filed Feb. 4, 2020, the entire content of which is incorporated herein by reference.

BACKGROUND

Technical Field

The present disclosure relates to a common-mode choke coil. More specifically, the present disclosure relates to a multilayer common-mode choke coil including a multilayer body with plural stacked non-conductor layers, and first and second coils incorporated in the multilayer body.

Background Art

A technique that is of interest for the present disclosure is described in, for example, Japanese Unexamined Patent Application Publication No. 2006-313946. The technique described in Japanese Unexamined Patent Application Publication No. 2006-313946 relates to a multilayer common-mode choke coil. The common-mode choke coil is an ultra-small thin-film common-mode choke coil, and capable of high-speed transmission of transmission signals at frequencies near the GHz range. More specifically, Japanese Unexamined Patent Application Publication No. 2006-313946 describes a common-mode choke coil with a cutoff frequency of greater than or equal to 2.4 GHz, the cutoff frequency being defined as the frequency at which the attenuation of a transmission signal (differential-mode signal) reaches -3 dB.

Advances in high-speed communication technology have led to the growing need for a multilayer common-mode choke coil that can, at increasingly higher frequencies, transmit differential-mode signals and attenuate common-mode noise components.

SUMMARY

Accordingly, the present disclosure provides a multilayer common-mode choke coil that can, at higher frequencies such as 25 GHz to 30 GHz, and even at very high frequencies such as above 30 GHz, transmit differential-mode signals, and suppress common-mode noise components.

A common-mode choke coil according to preferred embodiments of the present disclosure includes a multilayer body, a first coil, a second coil, a first terminal electrode, a second terminal electrode, a third terminal electrode, and a fourth terminal electrode. The multilayer body includes a plurality of non-conductor layers, the plurality of non-conductor layers being stacked and each made of a non-conductor. The first coil and the second coil are incorporated in the multilayer body. The first terminal electrode and the second terminal electrode are provided on an outer surface of the multilayer body, the first terminal electrode being electrically connected to a first end, the second terminal electrode being electrically connected to a second end, the first end and the second end being different ends of the first coil. The third terminal electrode and the fourth terminal electrode are provided on an outer surface of the multilayer body, the third terminal electrode being electrically connected to a third end, the fourth terminal electrode being

2

electrically connected to a fourth end, the third end and the fourth end being different ends of the second coil.

The plurality of non-conductor layers include a first plurality of non-conductor layers and a second plurality of non-conductor layers. The first coil includes a first coil conductor disposed along a first interface, the first interface being an interface between the first plurality of non-conductor layers. The second coil includes a second coil conductor disposed along a second interface, the second interface being an interface between the second plurality of non-conductor layers.

The multilayer body is a cuboid in shape having a first major face, a second major face, a first lateral face, a second lateral face, a first end face, and a second end face. The first major face and the second major face extend in a direction in which the plurality of non-conductor layers extend, and are opposite to each other. The first lateral face and the second lateral face couple the first major face and the second major face to each other, and are opposite to each other. The first end face and the second end face couple the first major face and the second major face to each other and couple the first lateral face and the second lateral face to each other, and are opposite to each other.

The first coil conductor is positioned with a first gap, a second gap, a third gap, and a fourth gap interposed respectively between the first coil conductor and the first lateral face, between the first coil conductor and the second lateral face, between the first coil conductor and the first end face, and between the first coil conductor and the second end face. The second coil conductor is positioned with a fifth gap, a sixth gap, a seventh gap, and an eighth gap interposed respectively between the second coil conductor and the first lateral face, between the second coil conductor and the second lateral face, between the second coil conductor and the first end face, and between the second coil conductor and the second end face.

To address the above-mentioned technical problem, according to preferred embodiments of the present disclosure, the difference between the first gap and the fifth gap has an absolute value DA1, the difference between the second gap and the sixth gap has an absolute value DA2, the difference between the third gap and the seventh gap has an absolute value DA3, and the difference between the fourth gap and the eighth gap has an absolute value DA4, and of the four absolute values DA1, DA2, DA3, and DA4, at least two absolute values are greater than or equal to 0.02 mm.

According to preferred embodiment of the present disclosure, the stray capacitance between the first coil and the second coil can be reduced to thereby improve high-frequency characteristics.

Other features, elements, characteristics and advantages of the present disclosure will become more apparent from the following detailed description of preferred embodiments of the present disclosure with reference to the attached drawings.

BRIEF DESCRIPTION OF THE DRAWINGS

FIG. 1 is a perspective view of a common-mode choke coil according to an embodiment of the present disclosure, illustrating the outward appearance of the common-mode choke coil;

FIG. 2 is an exploded plan view of the major components of the common-mode choke coil illustrated in FIG. 1;

FIG. 3 is a plan view of the common-mode choke coil illustrated in FIG. 1, representing a schematic see-through

illustration, as viewed in the direction of stacking, of first and second coils incorporated in a multilayer body;

FIG. 4 is a plan view of a first coil conductor included in the first coil of the common-mode choke coil illustrated in FIG. 1, explaining the number of turns of the first coil conductor;

FIG. 5 illustrates the transmission characteristic for common-mode components (Scc21 transmission characteristic) obtained for a common-mode choke coil corresponding to Sample 6 fabricated in an exemplary experiment conducted to verify the effects of the present disclosure;

FIG. 6 illustrates the transmission characteristic for differential-mode components (Sdd21 transmission characteristic) obtained for the common-mode choke coil corresponding to Sample 6;

FIG. 7 illustrates the transmission characteristic for common-mode components (Scc21 transmission characteristic) obtained for a common-mode choke coil corresponding to Sample 7 fabricated in the exemplary experiment;

FIG. 8 illustrates the transmission characteristic for differential-mode components (Sdd21 transmission characteristic) obtained for the common-mode choke coil corresponding to Sample 7;

FIG. 9 illustrates the transmission characteristic for common-mode components (Scc21 transmission characteristic) obtained for a common-mode choke coil corresponding to Sample 8 fabricated in the exemplary experiment;

FIG. 10 illustrates the transmission characteristic for differential-mode components (Sdd21 transmission characteristic) obtained for the common-mode choke coil corresponding to Sample 8;

FIG. 11 illustrates the transmission characteristic for common-mode components (Scc21 transmission characteristic) obtained for a common-mode choke coil corresponding to Sample 9 fabricated in the exemplary experiment;

FIG. 12 illustrates the transmission characteristic for differential-mode components (Sdd21 transmission characteristic) obtained for the common-mode choke coil corresponding to Sample 9;

FIG. 13 illustrates the transmission characteristic for common-mode components (Scc21 transmission characteristic) obtained for a common-mode choke coil corresponding to Sample 10 fabricated in the exemplary experiment; and

FIG. 14 illustrates the transmission characteristic for differential-mode components (Sdd21 transmission characteristic) obtained for the common-mode choke coil corresponding to Sample 10.

DETAILED DESCRIPTION

With reference to FIGS. 1 through 4, a common-mode choke coil 1 according to an embodiment of the present disclosure is described below.

As illustrated in FIG. 1, the common-mode choke coil 1 includes a multilayer body 2 having plural stacked non-conductor layers. FIG. 2 depicts representative non-conductor layers 3a, 3b, 3c, 3d, and 3e among these non-conductor layers. In the following description, unless individual non-conductor layers are to be distinguished from each other such as in the case of the non-conductor layers 3a, 3b, 3c, 3d, and 3e illustrated in FIG. 2, reference sign "3" is used for non-conductor layers to generically describe each non-conductor layer. Each non-conductor layer 3 is made of a non-conductor, examples of which include glass and ceramic materials.

The multilayer body 2 is substantially a cuboid in shape that has a first major face 5, a second major face 6, a first lateral face 7, a second lateral face 8, a first end face 9, and a second end face 10. The first major face 5 and the second major face 6 extend in the direction in which the non-conductor layers 3 extend, and are opposite to each other. The first lateral face 7 and the second lateral face 8 couple the first major face 5 and the second major face 6 to each other, and are opposite to each other. The first end face 9 and the second end face 10 couple the first major face 5 and the second major face 6 to each other and couple the first lateral face 7 and the second lateral face 8 to each other, and are opposite to each other. The cuboid may be, for example, rounded or chamfered in its edge and corner portions.

As illustrated in FIGS. 2 and 3, the common-mode choke coil 1 includes a first coil 11 and a second coil 12 that are incorporated in the multilayer body 2. As illustrated in FIG. 1, the common-mode choke coil 1 also includes the following terminal electrodes provided on the outer surface of the multilayer body 2: a first terminal electrode 13, a second terminal electrode 14, a third terminal electrode 15, and a fourth terminal electrode 16. More specifically, the first terminal electrode 13 and the third terminal electrode 15 are provided on the first lateral face 7, and the second terminal electrode 14 and the fourth terminal electrode 16, which are respectively symmetrical in shape to the first terminal electrode 13 and the third terminal electrode 15, are provided on the second lateral face 8.

As illustrated in FIG. 2, the first terminal electrode 13 and the second terminal electrode 14 are respectively electrically connected to a first end 11a and a second end 11b, which are different ends of the first coil 11. The third terminal electrode 15 and the fourth terminal electrode 16 are respectively electrically connected to a third end 12a and a fourth end 12b, which are different ends of the second coil 12.

The following description assumes that the non-conductor layers 3a, 3b, 3c, 3d, and 3e are stacked from the bottom to the top in the order depicted in FIG. 2.

Referring to FIG. 2, the first coil 11 has a first coil conductor 17 disposed along the interface between the non-conductor layers 3b and 3c. The first coil 11 has a first extended conductor 19, and a second extended conductor 20. The first extended conductor 19 provides the first coil 11 with the first end 11a. The second extended conductor 20 provides the first coil 11 with the second end 11b. The first extended conductor 19 includes a first connection end portion 23. The first connection end portion 23 is connected to the first terminal electrode 13 at a location on the outer surface of the multilayer body 2. The second extended conductor 20 includes a second connection end portion 24. The second connection end portion 24 is connected to the second terminal electrode 14 at a location on the outer surface of the multilayer body 2.

The first connection end portion 23 is disposed along the interface between the non-conductor layers 3a and 3b different from the interface between the non-conductor layers 3b and 3c along which the first coil conductor 17 is disposed. The first extended conductor 19 includes a first via-conductor 27, and a first coupling part 29. The first via-conductor 27 is connected to the first coil conductor 17, and penetrates the non-conductor layer 3b, which is located between the first coil conductor 17 and the first connection end portion 23, in the thickness direction of the non-conductor layer 3b. The first coupling part 29 is disposed along the interface between the non-conductor layers 3a and 3b along which the first connection end portion 23 is disposed. The first coupling part 29 connects the first via-conductor 27 and the first

connection end portion 23 to each other. The first coupling part 29 is preferably shaped to extend substantially linearly. This makes it possible to reduce the inductance resulting from the first coupling part 29, leading to improved high-frequency characteristics.

As described below, the second coil 12 also has elements similar to those of the first coil 11.

The second coil 12 includes a second coil conductor 18 disposed along the interface between the non-conductor layers 3c and 3d. The second coil 12 includes a third extended conductor 21, and a fourth extended conductor 22. The third extended conductor 21 provides the second coil 12 with the third end 12a. The fourth extended conductor 22 provides the second coil 12 with the fourth end 12b. The third extended conductor 21 includes a third connection end portion 25. The third connection end portion 25 is connected to the third terminal electrode 15 at a location on the outer surface of the multilayer body 2. The fourth extended conductor 22 includes a fourth connection end portion 26. The fourth connection end portion 26 is connected to the fourth terminal electrode 16 at a location on the outer surface of the multilayer body 2.

The third connection end portion 25 is disposed along the interface between the non-conductor layers 3d and 3e different from the interface between the non-conductor layers 3c and 3d along which the second coil conductor 18 is disposed. The third extended conductor 21 includes a second via-conductor 28, and a second coupling part 30. The second via-conductor 28 is connected to the second coil conductor 18, and penetrates the non-conductor layer 3d, which is located between the second coil conductor 18 and the third connection end portion 25, in the thickness direction of the non-conductor layer 3d. The second coupling part 30 is disposed along the interface between the non-conductor layers 3d and 3e along which the third connection end portion 25 is disposed. The second coupling part 30 connects the second via-conductor 28 and the third connection end portion 25 to each other. As with the first coupling part 29 mentioned above, the second coupling part 30 is preferably shaped to extend substantially linearly. This makes it possible to reduce the inductance resulting from the second coupling part 30, leading to improved high-frequency characteristics.

The common-mode choke coil 1 is mounted with the second major face 6 of the multilayer body 2 directed toward a mounting substrate. In one exemplary embodiment of the common-mode choke coil 1, the multilayer body 2 has a length dimension L of greater than or equal to about 0.55 mm and less than or equal to about 0.75 mm (i.e., from about 0.55 mm to about 0.75 mm), which is defined between the first and second end faces 9 and 10 that are opposite to each other, a width dimension W of greater than or equal to about 0.40 mm and less than or equal to about 0.60 mm (i.e., from about 0.40 mm to about 0.60 mm), which is defined between the first and second lateral faces 7 and 8 that are opposite to each other, and a height dimension H of greater than or equal to about 0.20 mm and less than or equal to about 0.40 mm (i.e., from about 0.20 mm to about 0.40 mm), which is defined between the first and second major faces 5 and second major face 6 that are opposite to each other.

As is apparent from FIGS. 2 and 3, the first and second coil conductors 17 and 18 of the common-mode choke coil 1 each preferably have a number of turns of less than about 2.

The number of turns mentioned above is defined as follows. The first coil conductor 17 and the second coil conductor 18 each have a portion that extends in a substan-

tially arcuate shape. Referring now to FIG. 4, the first coil conductor 17 of the first coil 11 is described below. As illustrated in FIG. 4, a tangent T is drawn sequentially along the outer periphery of the coil conductor 17 from the beginning end of the coil conductor 17 to the terminating end, and when the tangent T has rotated 360 degrees, this is defined as one turn. For the coil conductor 17 illustrated in FIG. 4, the tangent T has rotated approximately 307 degrees, and hence the number of turns of the coil conductor 17 can be defined as approximately 0.85. The number of turns is defined in the same manner also for the second coil conductor 18 of the second coil 12.

The smaller the number of turns of the first coil conductor 17 and the number of turns of the second coil conductor 18, the more the stray capacitance generated between the first coil 11 and the second coil 12 can be reduced. Hence, a smaller number of turns can contribute to improved high-frequency characteristics of the common-mode choke coil 1.

As clearly illustrated in FIG. 3, the common-mode choke coil 1 is preferably configured such that with the first coil conductor 17 and the second coil conductor 18 being viewed in plan in the stacking direction of the multilayer body 2, the first coil conductor 17 and the second coil conductor 18 have no portion where the two coil conductors overlap each other, except for a portion where the two coil conductors cross each other. That is, preferably, the first coil conductor 17 and the second coil conductor 18 have no portion where the two coil conductors run in parallel in the same direction while overlapping each other. As a result, the stray capacitance generated between the first coil 11 and the second coil 12 can be reduced. This can contribute to improved high-frequency characteristics of the common-mode choke coil 1.

As is apparent from FIG. 3, with the first coil conductor 17 and the second coil conductor 18 being viewed in plan in the stacking direction of the multilayer body 2, the first coil conductor 17 and the second coil conductor 18 cross each other at two locations. By ensuring that the first coil conductor 17 and the second coil conductor 18 cross each other at two or less locations in this way, the stray capacitance generated between the first coil conductor 17 and the second coil conductor 18 is reduced. This can contribute to improved high-frequency characteristics.

Preferably, the first coil conductor 17 and the second coil conductor 18 have a distance between each other of greater than or equal to about 6 μ m and less than or equal to about 26 μ m (i.e., from about 6 μ m to about 26 μ m). If the distance is less than about 6 μ m, this may cause the stray capacitance generated between the first coil conductor 17 and the second coil conductor 18 to become large enough to degrade high-frequency characteristics. By contrast, if the distance is greater than about 26 μ m, this may cause a decrease in the coefficient of coupling between the first coil 11 and the second coil 12.

Although each of the non-conductor layers 3a, 3b, 3c, 3d, and 3e is depicted in FIG. 2 as being a single layer, at least some of these non-conductor layers may be made up of plural layers. Accordingly, for example, the above-mentioned adjustment of the distance between the first coil conductor 17 and the second coil conductor 18 may be made either by changing the thickness of the non-conductor layer 3c formed as a single layer, or by changing the number of layers constituting the non-conductor layer 3c.

The terminal electrodes 13 to 16 extend over an area from the first major face 5 to the second major face 6. In this regard, each of the terminal electrodes 13 to 16 has a width on the first lateral face 7 or the second lateral face 8 (the width of the first terminal electrode 13 on the first lateral

face 7 is denoted by "W1" in FIG. 1) of preferably greater than or equal to about 0.1 mm and less than or equal to about 0.25 mm (i.e., from about 0.1 mm to about 0.25 mm), more preferably greater than or equal to about 0.15 mm. If the line width is less than about 0.1 mm, this may result in insufficient fixing strength when the common-mode choke coil 1 is mounted onto the mounting substrate. By contrast, if the line width is greater than about 0.25 mm, this may cause Scc21, which represents the transmission characteristic of the common-mode choke coil 1 for common-mode components, to peak at a frequency of less than about 30 GHz.

Each of the terminal electrodes 13 to 16 is depicted in FIG. 1 as being partially extended to the first major face 5. Although not depicted in FIG. 1, each of the terminal electrodes 13 to 16 is partially extended also to the second major face 6. This extended portion has a dimension E of preferably greater than or equal to about 0.02 mm and less than or equal to about 0.2 mm (i.e., from about 0.02 mm to about 0.2 mm), more preferably less than or equal to about 0.17 mm. A dimension E less than about 0.02 mm may cause a decrease in the strength with which the common-mode choke coil 1 is fixed to the mounting substrate when mounted onto the mounting substrate. By contrast, a dimension E greater than about 0.2 mm may cause Scc21, which represents the transmission characteristic of the common-mode choke coil 1 for common-mode components, to peak at a frequency of less than about 30 GHz.

The common-mode choke coil 1 has characteristic features described below.

The first coil conductor 17 of the first coil 11 is positioned with a first gap SG1, a second gap SG2, a third gap SG3, and a fourth gap SG4 interposed respectively between the first coil conductor 17 and the first lateral face 7 of the multilayer body 2, between the first coil conductor 17 and the second lateral face 8, between the first coil conductor 17 and the first end face 9, and between the first coil conductor 17 and the second end face 10. The second coil conductor 18 of the second coil 12 is positioned with a fifth gap SG5, a sixth gap SG6, a seventh gap SG7, and an eighth gap SG8 interposed respectively between the second coil conductor 18 and the first lateral face 7 of the multilayer body 2, between the second coil conductor 18 and the second lateral face 8, between the second coil conductor 18 and the first end face 9, and between the second coil conductor 18 and the second end face 10.

As described below, attention is now directed to the absolute value of the difference between the first gap SG1 and the fifth gap SG5, the absolute value of the difference between the second gap SG2 and the sixth gap SG6, the absolute value of the difference between the third gap SG3 and the seventh gap SG7, and the absolute value of the difference between the fourth gap SG4 and the eighth gap SG8.

The difference between the first gap SG1 and the fifth gap SG5 has an absolute value DA1, the difference between the second gap SG2 and the sixth gap SG6 has an absolute value DA2, the difference between the third gap SG3 and the seventh gap SG7 has an absolute value DA3, and the difference between the fourth gap SG4 and the eighth gap SG8 has an absolute value DA4. In this case, the common-mode choke coil 1 is configured such that at least two of the four absolute values DA1, DA2, DA3, and DA4 are greater than or equal to about 0.02 mm.

As will be apparent from an exemplary experiment described later, the above-mentioned characteristic configuration makes it possible to reduce the stray capacitance generated between the first coil 11 and the second coil 12,

more specifically, the stray capacitance generated between the first coil conductor 17 and the second coil conductor 18. This results in improved high-frequency characteristics of the common-mode choke coil 1. More specifically, the above-mentioned configuration helps to ensure that with respect to the transmission characteristic (Scc21 transmission characteristic) for common-mode components, its peak is located at a frequency of greater than or equal to about 24 GHz, and the peak has a value (minimum value) of less than or equal to about -20 dB, and that with respect to the transmission characteristic (Sdd21 transmission characteristic) for differential-mode components, the transmission characteristic becomes about -2.5 dB at a frequency of greater than or equal to about 30 GHz.

Preferably, all of the four absolute values DA1, DA2, DA3, and DA4 are greater than or equal to about 0.02 mm. This makes it possible to obtain a desired Scc21 transmission characteristic and a desired Sdd21 transmission characteristic in a stable manner.

Preferably, at least two of the four absolute values DA1, DA2, DA3, and DA4 are greater than or equal to about 0.04 mm. This helps to ensure that for the Sdd21 transmission characteristic, the transmission characteristic becomes about -1.5 dB at a frequency of greater than or equal to about 30 GHz.

Preferably, at least two of the four absolute values DA1, DA2, DA3, and DA4 are less than or equal to about 0.08 mm. This helps to prevent the inductance of one of the first and second coils from becoming too small.

Preferably, at least three of the four absolute values DA1, DA2, DA3, and DA4 excluding the largest one of the four absolute values are equal to each other. This allows all of the three absolute values to be made greater than or equal to about 0.02 mm without considering the relative magnitudes of the three absolute values. As a result, the common-mode choke coil can be simplified in design.

Preferably, each of the first coil conductor 17 and the second coil conductor 18 has a line width of greater than or equal to about 10 μ m and less than or equal to about 24 μ m (i.e., from about 10 μ m to about 24 μ m). If the line width is less than about 10 μ m, this may cause the coil conductors 17 and 18 to have an increased direct-current resistance. By contrast, if the line width is greater than about 24 μ m, this may cause the stray capacitance generated between the first coil conductor 17 and the second coil conductor 18 to become large enough to degrade high-frequency characteristics.

Each of the first coil conductor 17 and the second coil conductor 18 has a line width of preferably less than or equal to about 18 μ m (0.018 mm). In this case, if the smallest one of the four absolute values DA1, DA2, DA3, and DA4 is made greater than or equal to about 0.02 mm, this helps to ensure that the first coil conductor 17 and the second coil conductor 18 have no portion where the two coil conductors overlap each other, except for a portion where the two coil conductors cross each other. This can also contribute to reducing the stray capacitance generated between the first coil conductor 17 and the second coil conductor 18, and consequently, improving high-frequency characteristics.

As is apparent from FIGS. 2 and 3, in the embodiment, the third gap SG3 is extremely large in comparison to the other gaps SG1, SG2, and SG4 associated with the first coil conductor 17. Thus, the absolute value DA3 of the difference between the third gap SG3 and the seventh gap SG7 is the largest of the four absolute values DA1, DA2, DA3, and DA4. The third gap SG3 is extremely large as described above because, as a way to reduce the stray capacitance

generated between the first coil conductor **17** and the second coil conductor **18**, a design is employed in which the first coil conductor **17** has a reduced number of turns and the first coil **11** has a shorter path length.

Reference is now made to a preferred manufacturing method for the common-mode choke coil **1**.

The following process is performed to produce a glass-ceramic sheet that is to become each non-conductor layer **3**. First, K_2O , B_2O_3 , and SiO_2 , and as required, Al_2O_3 are weighed in a predetermined ratio, put into a crucible made of platinum, and melted by being raised to a temperature of about 1500 to 1600° C. in a firing furnace. The resulting melted substance is rapidly cooled to yield a glass material.

An example of the above-mentioned glass material is a glass material containing at least K, B, and Si, with K contained at a K_2O equivalent of about 0.5 to 5 mass %, B at a B_2O_3 equivalent of about 10 to 25 mass %, Si at an SiO_2 equivalent of about 70 to 85 mass %, and Al at an Al_2O_3 equivalent of about 0 to 5 mass %.

Subsequently, the above-mentioned glass material is pulverized to obtain glass powder with a D50 particle size (particle size equivalent to 50% of the volume-based cumulative percentage) of about 1 to 3 m.

Subsequently, alumina powder and quartz (SiO_2) powder both having a D50 particle size of about 0.5 to 2.0 μm are added to the above-mentioned glass powder. The resulting powder is charged into a ball mill together with PSZ media. Further, an organic binder such as a polyvinyl butyral-based organic binder, an organic solvent such as ethanol or toluene, and a plasticizer are charged into the ball mill and mixed together to obtain a glass-ceramic slurry.

Then, the slurry is formed into a sheet with a film thickness of about 20 to 30 μm by a method such as the doctor blade method, and the obtained sheet is punched in a substantially rectangular shape. Plural glass-ceramic sheets are thus obtained.

Examples of inorganic components contained in each glass-ceramic sheet mentioned above include a dielectric glass material containing about 60 to 66 mass % of a glass material, about 34 to 37 mass % of quartz, and about 0.5 to 4 mass % of alumina.

Meanwhile, a conductive paste containing Ag as a conductive component and used for forming the first coil **11** and the second coil **12** is prepared.

Subsequently, a predetermined glass-ceramic sheet is subjected to, for example, irradiation with laser light to thereby provide the glass-ceramic sheet with a through-hole in which to place each of via-conductors **27** and **28**. Then, the conductive paste is applied to the predetermined glass-ceramic sheet by, for example, screen printing. Thus, the via-conductors **27** and **28** with the conductive paste filling the above-mentioned through-hole are formed, and the coil conductors **17** and **18**, the connection end portions **23** to **26** respectively constituting the extended conductors **19** to **22**, and the coupling parts **29** and **30** are formed in a patterned state.

Subsequently, plural glass-ceramic sheets are stacked such that the non-conductor layers **3a** to **3e** stacked in the order illustrated in FIG. 2 can be obtained. At this time, on the top and bottom of the stack of these glass-ceramic sheets, a suitable number of glass-ceramic sheets with no through-hole provided therein and no conductive paste applied thereto are further stacked as required.

Subsequently, the stacked glass-ceramic sheets are subjected to a warm isotropic press process at a temperature of about 80° C. and a pressure of about 100 MPa to obtain a multilayer block.

Subsequently, the multilayer block is cut with a dicer or other device into individual discrete multilayer structures each dimensioned such that the multilayer structure can become the multilayer body **2** of each individual common-mode choke coil **1**.

Subsequently, each discrete multilayer structure thus obtained is fired in a firing furnace at a temperature of about 860 to 900° C. for about 1 to 2 hours, for example, at a temperature of about 880° C. for about 1.5 hours to thereby obtain the multilayer body **2**.

The fired multilayer body **2** is preferably placed into a rotating barrel together with media. Then, as the multilayer body **2** is rotated, the edge and corner portions of the multilayer body **2** are rounded or chamfered.

Subsequently, a conductive paste containing Ag and glass is applied to portions of the multilayer body **2** to which the connection end portions **23** to **26** are extended. Then, the conductive paste is baked at a temperature of, for example, about 810° C. for about 1 minute to thereby form an underlying film for each of the terminal electrodes **13** to **16**. The underlying film has a thickness of, for example, about 5 m. Then, for example, a Ni film and a Sn film are formed sequentially on the underlying film by electroplating. The Ni film and the Sn film each have a thickness of, for example, about 3 m.

In this way, the common-mode choke coil **1** illustrated in FIG. 1 is completed.

As described above, by making at least two of the four absolute values DA1, DA2, DA3, and DA4 greater than or equal to about 0.02 mm, the high-frequency characteristics of the common-mode choke coil **1** can be improved. An experiment conducted to verify this observation is now described below.

Exemplary Experiment

Common-mode choke coils corresponding to various samples each have a multilayer body dimensioned to have a length dimension L of 0.65 mm, a width dimension W of 0.50 mm, and a height dimension H of 0.30 mm.

Each sample is described below with reference to FIG. 2. As illustrated in Tables 1A and 1B, Sample (indicated as "S" in Tables 1A and 1B) 1 to Sample 20 are prepared by varying the following values:

"SG4", "SG2", and "SG1" with respect to the first coil conductor **17**;

"SG5 to SG8" with respect to the second coil conductor **18**;

"SG difference"; and

"line width".

With regard to the first coil conductor **17**, the gap SG3 is extremely large in comparison to the other gaps SG4, SG2, and SG1, and thus the absolute value of SG difference corresponding to the gap SG3 is the largest of all such absolute values. Therefore, the scope of the present disclosure can be determined based on whether the second largest absolute value of SG difference is greater than or equal to a predetermined value. Accordingly, Table 1A illustrates only the gaps excluding the gap SG3, that is, the gaps "SG4", "SG2", and "SG1". For Samples 1 to 14, the gaps "SG4", "SG2", and "SG1" are set equal to each other. For Samples 15 to 20, the gaps "SG4", "SG2", and "SG1" are indicated individually.

With respect to the second coil conductor **18**, the gaps SG5, SG6, SG7, and SG8 are set equal to each other, and indicated as "SG5 to SG8".

As described above, the "SG difference" represents the second largest absolute value of SG difference. That is, since the gap SG3 is excluded, the "SG difference" represents the

11

largest one of the following absolute values: the absolute value of the difference between the gaps SG1 and SG5; the absolute value of the difference between the gaps SG2 and SG6; and the absolute value of the difference between the gaps SG4 and SG8.

As for "line width", the first coil conductor **17** and the second coil conductor **18** are made equal in line width, and the line width of each of the coil conductors **17** and **18** is indicated.

For each of the common-mode choke coils corresponding to Samples 1 to 20 above, the transmission characteristic for common-mode components (Scc21 transmission characteristic) and the transmission characteristic for differential-mode components (Sdd21 transmission characteristic) are obtained.

FIG. 5 and FIG. 6 respectively illustrate the Scc21 transmission characteristic and the Sdd21 transmission characteristic obtained for the common-mode choke coil corresponding to Sample 6.

FIG. 7 and FIG. 8 respectively illustrate the Scc21 transmission characteristic and the Sdd21 transmission characteristic obtained for the common-mode choke coil corresponding to Sample 7.

FIG. 9 and FIG. 10 respectively illustrate the Scc21 transmission characteristic and the Sdd21 transmission characteristic obtained for the common-mode choke coil corresponding to Sample 8.

FIG. 11 and FIG. 12 respectively illustrate the Scc21 transmission characteristic and the Sdd21 transmission characteristic obtained for the common-mode choke coil corresponding to Sample 9.

FIG. 13 and FIG. 14 respectively illustrate the Scc21 transmission characteristic and the Sdd21 transmission characteristic obtained for the common-mode choke coil corresponding to Sample 10.

From the characteristic charts in FIGS. 5 and 6, for Sample 6, the peak position and the minimum value (transmission coefficient at the peak position) with respect to the Scc21 transmission characteristic, and the respective transmission coefficients at 20 GHz, 30 GHz, and 40 GHz with respect to the Sdd21 transmission characteristic are obtained.

Likewise, the peak position and the minimum value (transmission coefficient at the peak position) with respect to the Scc21 transmission characteristic, and the respective transmission coefficients at 20 GHz, 30 GHz, and 40 GHz with respect to the Sdd21 transmission characteristic are obtained for Sample 7 from FIGS. 7 and 8, for Sample 8 from FIGS. 9 and 10, for Sample 9 from FIGS. 11 and 12, and for Sample 10 from FIGS. 13 and 14. Although the corresponding characteristic charts are not illustrated, for Samples 1 to 5 and 11 to 20 as well, the peak position and the minimum value (transmission coefficient at the peak position) with respect to the Scc21 transmission characteristic, and the respective transmission coefficients at 20 GHz, 30 GHz, and 40 GHz with respect to the Sdd21 transmission characteristic are obtained in the same manner as mentioned above. The results are illustrated in Tables 1A and 1B.

In Table 1B, the evaluation (indicated as "EV" in Table 1B) for a sample is "pass" (marked "P") if the peak position of the Scc21 characteristic, that is, the frequency at which the transmission coefficient is minimum is located at or above 24 GHz, and the evaluation is "fail" (marked "F") if this peak is located below 24 GHz.

Further, the evaluation is "pass" (marked "P") if the minimum transmission coefficient of the Scc21 characteristic, that is, the transmission coefficient at the peak position

12

is less than or equal to -20 dB, and the evaluation is "fail" (marked "F") if this minimum transmission coefficient is greater than -20 dB. In Table 1B, no sample is marked "F".

With respect to the transmission coefficient at 20 GHz of the Sdd21 characteristic, a sample is evaluated as: the most favorable (excellent) (marked "E") if this transmission coefficient is greater than or equal to -1.5 dB; the next most favorable (pass) (marked "P") if this transmission coefficient is greater than or equal to -2.5 dB and less than -1.5 dB (i.e., from -2.5 dB to less than -1.5 dB); and poor (fail) (marked "F") if this transmission coefficient is less than -2.5 dB.

Likewise, with respect to the transmission coefficient at 30 GHz of the Sdd21 characteristic, a sample is evaluated as: the most favorable (excellent) (marked "E") if this transmission coefficient is greater than or equal to -1.5 dB; the next most favorable (pass) (marked "P") if this transmission coefficient is greater than or equal to -2.5 dB and less than -1.5 dB (i.e., from -2.5 dB to less than -1.5 dB); and poor (fail) (marked "F") if this transmission coefficient is less than -2.5 dB.

Likewise, with respect to the transmission coefficient at 40 GHz of the Sdd21 characteristic, a sample is evaluated as: the most favorable (excellent) (marked "E") if this transmission coefficient is greater than or equal to -1.5 dB; the next most favorable (pass) (marked "P") if this transmission coefficient is greater than or equal to -2.5 dB and less than -1.5 dB (i.e., from -2.5 dB to less than -1.5 dB); and poor (fail) (marked "F") if this transmission coefficient is less than -2.5 dB.

In Table 1A, Samples 1 and 10 each have an "SG difference" of 0, and hence do not satisfy the condition that the "SG difference" be greater than or equal to 0.02 mm. Accordingly, for Sample 1, the peak position of the Scc21 transmission characteristic is 21.50 GHz, which is less than 24 GHz. This means that common-mode noise components are not sufficiently attenuated at higher frequencies. For Sample 10, the transmission coefficient at 30 GHz with respect to the Sdd21 transmission characteristic is -2.80 dB, which is less than -2.5 dB. This means that the sample disadvantageously attenuates differential-mode signals at 35 higher frequencies.

By contrast, for Samples 2 to 9 and 11 to 20 that satisfy the condition that the "SG difference" be greater than or equal to 0.02 mm, the peak position of the Scc21 transmission characteristic is greater than or equal to 24 GHz. This allows for sufficient attenuation of common-mode noise components at higher frequencies. Further, with respect to the Sdd21 transmission characteristic, the transmission coefficient at 30 GHz is greater than or equal to -2.5 dB. This helps to ensure that, at higher frequencies, differential-mode signals can be transmitted without being attenuated.

Each of Samples 3 to 8 and 11 to 20 has an "SG difference" of greater than or equal to 0.04 mm. A comparison between Samples 3 to 8 and 11 to 14 of these samples, and Samples 2 and 9, which each have an "SG difference" of 0.02 mm, reveals that with respect to the Sdd21 transmission characteristic, the transmission coefficient at 30 GHz and the transmission coefficient at 40 GHz are observed to differ between these two sets of samples. That is, higher transmission coefficients are observed for Samples 3 to 8 and 11 to 14 with an "SG difference" of greater than or equal to 0.04 mm, than for Samples 2 and 9 with an "SG difference" of 0.02 mm.

Although the present disclosure has been described above with reference to the illustrated embodiment, various other modifications are possible within the scope of the present disclosure.

For example, in one alternative embodiment, a single coil conductor included in at least one of the first and second coils may be divided in two into a first portion and a second portion, the first portion and the second portion may be disposed respectively along a first interface and a second

interface, which are different interfaces between non-conductor layers, and the first portion and the second portion may be connected by a via-conductor.

While preferred embodiments of the disclosure have been described above, it is to be understood that variations and modifications will be apparent to those skilled in the art without departing from the scope and spirit of the disclosure. The scope of the disclosure, therefore, is to be determined solely by the following claims.

What is claimed is:

1. A common-mode choke coil comprising:
a multilayer body including a plurality of non-conductor layers, the plurality of non-conductor layers being stacked and each made of a non-conductor, and the plurality of non-conductor layers including a first plurality of non-conductor layers and a second plurality of non-conductor layers;
a first coil and a second coil that are incorporated in the multilayer body, the first coil having a first end and a second end which are different ends of the first coil, the second coil having a third end and a fourth end which are different ends of the second coil, the first coil including a first coil conductor disposed along a first interface which is an interface between the first plurality of non-conductor layers, and the second coil including a second coil conductor disposed along a second interface which is an interface between the second plurality of non-conductor layers and different from the first interface along which the first coil conductor is disposed;
a first terminal electrode and a second terminal electrode that are provided on an outer surface of the multilayer body, the first terminal electrode being electrically connected to the first end, and the second terminal electrode being electrically connected to a second end; and
a third terminal electrode and a fourth terminal electrode that are provided on an outer surface of the multilayer body, the third terminal electrode being electrically connected to the third end, the fourth terminal electrode being electrically connected to the fourth end,
wherein the multilayer body is a cuboid in shape, the cuboid having
a first major face and a second major face that extend in a direction in which the plurality of non-conductor layers extend, the first major face and the second major face being opposite to each other,
a first lateral face and a second lateral face that couple the first major face and the second major face to each other, the first lateral face and the second lateral face being opposite to each other, and
a first end face and a second end face that couple the first major face and the second major face to each other and couple the first lateral face and the second lateral face to each other, the first end face and the second end face being opposite to each other,
wherein the first coil conductor is positioned with a first gap, a second gap, a third gap, and a fourth gap interposed respectively between the first coil conductor and the first lateral face, between the first coil conductor and the second lateral face, between the first coil conductor and the first end face, and between the first coil conductor and the second end face,
wherein the second coil conductor is positioned with a fifth gap, a sixth gap, a seventh gap, and an eighth gap interposed respectively between the second coil conductor and the first lateral face, between the second coil

15

conductor and the second lateral face, between the second coil conductor and the first end face, and between the second coil conductor and the second end face,

wherein a difference between the first gap and the fifth gap has an absolute value DA1, a difference between the second gap and the sixth gap has an absolute value DA2, a difference between the third gap and the seventh gap has an absolute value DA3, and a difference between the fourth gap and the eighth gap has an absolute value DA4,

wherein of four absolute values comprising the absolute value DA1, the absolute value DA2, the absolute value DA3, and the absolute value DA4, at least two absolute values are greater than or equal to 0.02 mm, and wherein in a view perpendicular to a non-conductor layer of the plurality of non-conductor layers, an imaginary line extending perpendicularly from the first lateral face to the second lateral face extends through the first coil conductor, then through the second coil conductor in at least two different locations, and then through the first conductor directly to the second lateral face.

2. The common-mode choke coil according to claim 1, wherein

all of the four absolute values DA1, DA2, DA3, and DA4 are greater than or equal to 0.02 mm.

3. The common-mode choke coil according to claim 2, wherein

at least two absolute values of the four absolute values DA1, DA2, DA3, and DA4 are greater than or equal to 0.04 mm.

4. The common-mode choke coil according to claim 2, wherein

at least two absolute values of the four absolute values DA1, DA2, DA3, and DA4 are less than or equal to 0.08 mm.

5. The common-mode choke coil according to claim 2, wherein

of the four absolute values DA1, DA2, DA3, and DA4, three absolute values excluding a largest one of the four absolute values DA1, DA2, DA3, and DA4 are equal to each other.

6. The common-mode choke coil according to claim 2, wherein

the first coil conductor and the second coil conductor each have a line width of less than or equal to 0.024 mm.

7. The common-mode choke coil according to claim 2, wherein

the first terminal electrode and the third terminal electrode are provided on the first lateral face, and the second terminal electrode and the fourth terminal electrode are provided on the second lateral face, and one of the absolute value DA3 and the absolute value DA4 is a largest absolute value of the four absolute values DA1, DA2, DA3, and DA4.

8. The common-mode choke coil according to claim 1, wherein

at least two absolute values of the four absolute values DA1, DA2, DA3, and DA4 are greater than or equal to 0.04 mm.

9. The common-mode choke coil according to claim 8, wherein

at least two absolute values of the four absolute values DA1, DA2, DA3, and DA4 are less than or equal to 0.08 mm.

16

10. The common-mode choke coil according to claim 8, wherein

of the four absolute values DA1, DA2, DA3, and DA4, three absolute values excluding a largest one of the four absolute values DA1, DA2, DA3, and DA4 are equal to each other.

11. The common-mode choke coil according to claim 8, wherein

the first coil conductor and the second coil conductor each have a line width of less than or equal to 0.024 mm.

12. The common-mode choke coil according to claim 1, wherein

at least two absolute values of the four absolute values DA1, DA2, DA3, and DA4 are less than or equal to 0.08 mm.

13. The common-mode choke coil according to claim 12, wherein

of the four absolute values DA1, DA2, DA3, and DA4, three absolute values excluding a largest one of the four absolute values DA1, DA2, DA3, and DA4 are equal to each other.

14. The common-mode choke coil according to claim 1, wherein

of the four absolute values DA1, DA2, DA3, and DA4, three absolute values excluding a largest one of the four absolute values DA1, DA2, DA3, and DA4 are equal to each other.

15. The common-mode choke coil according to claim 1, wherein

the first coil conductor and the second coil conductor each have a line width of less than or equal to 0.024 mm.

16. The common-mode choke coil according to claim 15, wherein

a smallest absolute value of the four absolute values DA1, DA2, DA3, and DA4 is greater than or equal to 0.02 mm.

17. The common-mode choke coil according to claim 1, wherein

the first coil conductor and the second coil conductor each have a line width of greater than or equal to 0.01 mm.

18. The common-mode choke coil according to claim 1, wherein

the first terminal electrode and the third terminal electrode are provided on the first lateral face, and the second terminal electrode and the fourth terminal electrode are provided on the second lateral face, and

one of the absolute value DA3 and the absolute value DA4 is a largest absolute value of the four absolute values DA1, DA2, DA3, and DA4.

19. A common-mode choke coil comprising:

a multilayer body including a plurality of non-conductor layers, the plurality of non-conductor layers being stacked and each made of a non-conductor, and the plurality of non-conductor layers including a first plurality of non-conductor layers and a second plurality of non-conductor layers;

a first coil and a second coil that are incorporated in the multilayer body, the first coil having a first end and a second end which are different ends of the first coil, the second coil having a third end and a fourth end which are different ends of the second coil, the first coil including a first coil conductor disposed along a first interface which is an interface between the first plurality of non-conductor layers, and the second coil including a second coil conductor disposed along a second interface which is an interface between the second

17

plurality of non-conductor layers and different from the first interface along which the first coil conductor is disposed;

a first terminal electrode and a second terminal electrode that are provided on an outer surface of the multilayer body, the first terminal electrode being electrically connected to the first end, and the second terminal electrode being electrically connected to a second end; and

a third terminal electrode and a fourth terminal electrode that are provided on an outer surface of the multilayer body, the third terminal electrode being electrically connected to the third end, the fourth terminal electrode being electrically connected to the fourth end, wherein the multilayer body is a cuboid in shape, the cuboid having

a first major face and a second major face that extend in a direction in which the plurality of non-conductor layers extend, the first major face and the second major face being opposite to each other,

a first lateral face and a second lateral face that couple the first major face and the second major face to each other, the first lateral face and the second lateral face being opposite to each other, and

a first end face and a second end face that couple the first major face and the second major face to each other and couple the first lateral face and the second lateral face to each other, the first end face and the second end face being opposite to each other,

wherein the first coil conductor is positioned with a first gap, a second gap, a third gap, and a fourth gap interposed respectively between the first coil conductor and the first lateral face, between the first coil conductor and the second lateral face, between the first coil conductor and the first end face, and between the first coil conductor and the second end face,

wherein the second coil conductor is positioned with a fifth gap, a sixth gap, a seventh gap, and an eighth gap interposed respectively between the second coil conductor and the first lateral face, between the second coil conductor and the second lateral face, between the second coil conductor and the first end face, and between the second coil conductor and the second end face,

wherein a difference between the first gap and the fifth gap has an absolute value DA1, a difference between the second gap and the sixth gap has an absolute value DA2, a difference between the third gap and the seventh gap has an absolute value DA3, and a difference between the fourth gap and the eighth gap has an absolute value DA4,

wherein of four absolute values comprising the absolute value DA1, the absolute value DA2, the absolute value DA3, and the absolute value DA4, at least two absolute values are greater than or equal to 0.02 mm, and

wherein the first gap is smaller than the fifth gap and the second gap is smaller than the sixth gap.

20. A common-mode choke coil comprising:

a multilayer body including a plurality of non-conductor layers, the plurality of non-conductor layers being stacked and each made of a non-conductor, and the plurality of non-conductor layers including a first plurality of non-conductor layers and a second plurality of non-conductor layers;

a first coil and a second coil that are incorporated in the multilayer body, the first coil having a first end and a second end which are different ends of the first coil, the

18

second coil having a third end and a fourth end which are different ends of the second coil, the first coil including a first coil conductor disposed along a first interface which is an interface between the first plurality of non-conductor layers, and the second coil including a second coil conductor disposed along a second interface which is an interface between the second plurality of non-conductor layers and different from the first interface along which the first coil conductor is disposed;

a first terminal electrode and a second terminal electrode that are provided on an outer surface of the multilayer body, the first terminal electrode being electrically connected to the first end, and the second terminal electrode being electrically connected to a second end; and

a third terminal electrode and a fourth terminal electrode that are provided on an outer surface of the multilayer body, the third terminal electrode being electrically connected to the third end, the fourth terminal electrode being electrically connected to the fourth end, wherein the multilayer body is a cuboid in shape, the cuboid having

a first major face and a second major face that extend in a direction in which the plurality of non-conductor layers extend, the first major face and the second major face being opposite to each other,

a first lateral face and a second lateral face that couple the first major face and the second major face to each other, the first lateral face and the second lateral face being opposite to each other, and

a first end face and a second end face that couple the first major face and the second major face to each other and couple the first lateral face and the second lateral face to each other, the first end face and the second end face being opposite to each other,

wherein the first coil conductor is positioned with a first gap, a second gap, a third gap, and a fourth gap interposed respectively between the first coil conductor and the first lateral face, between the first coil conductor and the second lateral face, between the first coil conductor and the first end face, and between the first coil conductor and the second end face,

wherein the second coil conductor is positioned with a fifth gap, a sixth gap, a seventh gap, and an eighth gap interposed respectively between the second coil conductor and the first lateral face, between the second coil conductor and the second lateral face, between the second coil conductor and the first end face, and between the second coil conductor and the second end face,

wherein a difference between the first gap and the fifth gap has an absolute value DA1, a difference between the second gap and the sixth gap has an absolute value DA2, a difference between the third gap and the seventh gap has an absolute value DA3, and a difference between the fourth gap and the eighth gap has an absolute value DA4,

wherein of four absolute values comprising the absolute value DA1, the absolute value DA2, the absolute value DA3, and the absolute value DA4, at least two absolute values are greater than or equal to 0.02 mm, and

wherein the first coil conductor includes a curvilinear section that extends from the first gap to the second gap.
